United States Patent Office.

WILLIAM HASLAM, OF PHILADELPHIA, PENNSYLVANIA, ASSIGNOR TO
HENRY TROEMNER, OF SAME PLACE.

Design No. 3,893, dated March 8, 1870.

DESIGN FOR A SPICE-MILL.

The Schedule referred to in these Letters Patent and making part of the same.

To all whom it may concern:

Be it known that I, WILLIAM HASLAM, of the city of Philadelphia, and State of Pennsylvania, have originated a new Design for a Spice-Mill, of which the following is a full, clear, and exact description, reference being had to the accompanying drawings making part of this specification.

Figure 1, A represents the base part of the mill, the top of which is a heavy molding of the form combining a half round and ogee-shape.

Fig. 1, B represents the end of base part of the mill, with round corners, paneled, the centre of end panel ornamented with a heavy Elizabethan style shield.

Fig. 1, D is the side or drawer front, with molding around the edges and knob in the center of the same.

Figure 2, E represents the casing which incloses the machinery for the grinding of spices. Said casing is of circular form until near the top of the base,

where it terminates with a short straight line, then with a hollow and a round combining, as shown in fig. 2.

F, also a projecting socket in the centre of casing E, through which a shaft passes, connecting with fly-wheel, Figure 4, G.

Figure 3, H represents the hopper, of circular form, connecting with the casing as seen in fig. 2, E.

Fig. 4, G is the fly-wheel, with a circular rim with six arms attached, and hub to which the shaft is made fast, said shaft passing through casing, as seen in fig. 2, E.

What I claim as my invention, and desire to secure by Letters Patent, is—

The design for a spice-mill herein set forth.

WILLIAM HASLAM [L. S.]
